UNITED STATES PATENT OFFICE

157,437

TIRE

Enzo A. Salcy, Arlington, Mass.

Application June 26, 1948, Serial No. 147,214

Term of patent 7 years

(Cl. D90—20)

To all whom it may concern:

Be it known that I, Enzo A. Salcy, a citizen of the United States of America, residing at Arlington, in the county of Middlesex and Commonwealth of Massachusetts, have invented a new, original, and ornamental Design for Tire, of which the following is a specification, reference being had to the accompanying drawing, forming part thereof.

Figure 1 is a plan view of a tire showing my new design;

Figure 2 is a cross-section thereof taken on the plane indicated 2—2 in Figure 1;

Figure 3 is a sectional view taken on the plane indicated 3—3 in Figure 1.

I claim:

The ornamental design for a tire, as shown.
ENZO A. SALCY.
